REGISTERING DEVICE FOR MULTICOLOR PRINTING

Frederick Shurley, Windsor, Ontario, Canada

Application July 3, 1939, Serial No. 282,729

3 Claims. (CL. 101—115)

This invention relates to a machine of the general type disclosed in my Letters Patent No. 2,060,385, for printing designs, trade-marks and/or other insignia directly upon articles having a hard, impenetrable surface, such as bottles, jars, tumblers, bulbs, cans, and the like, made from a wide variety of materials, as for example, glass, synthetic resin, or metal.

In machines of the class above designated the articles are usually supported in relation to a screen or printing devices, and each article is rotated upon its own axis, the articles being operated upon individually while so turning, by any suitable form of mechanism, which may be of the nature of printing mechanism, of which an example is shown in said Letters Patent No. 2,060,385.

In multi-color printing upon such articles, it is important to provide for exact registry of each article with the printing means at the printing station, and the present invention consists in its broad generic aspect of means to sense the position of each article as it moves toward the printing station; and to arrest each article in its desired rotative position in the carrier preliminary to the printing operation, then releasing the article and rotating it about its axis as the printing is effected.

With these objects in mind, the invention includes the provision of sensing means adapted to contact a projection upon the exterior of the article as the same is rotated about its own axis; and the provision of electrical circuits, including a relay circuit in which the sensing device is included, and a brake-operating circuit controlled by the relay circuit and acting to arrest the rotation of the article under control by the sensing device.

The invention also provides a registering device for multi-color printing wherein each article to be registered is rotated in turn until a projection thereon has been contacted by a needle, which occurs when the article has been turned to its desired rotary position, and whereupon the article is gripped and held immovable until it has been moved to printing position and actual printing is about to commence.

The invention also is to provide such a registering device for multi-color printing wherein means are provided for retaining the needle in contact with each article in turn as it is being registered, even if the periphery of the article is not truly circular.

The instant invention relates more particularly to registering devices of the same general type

as that shown and described in my co-pending application Serial No. 256,308, now Patent No. 2,229,347.

These and other features of the invention will be shown in the accompanying drawings, and described hereinafter, and finally pointed out in the claims.

In the accompanying drawings, like reference characters are applied to corresponding parts throughout the several views which make up the drawings, in which:

Figure 1 illustrates a side elevation of the assembly of my invention and a portion of a printing machine to which it is applied.

Figure 2 is an enlarged sectional view taken on the line 2—2 of Figure 1, and

Figure 3 is an enlarged section on the line 3—3 of Figure 1.

Figure 4 is an end view of the tubular arm and the casing mounted thereon for mounting the electromagnetic pick-up senser.

Figure 5 is an enlarged end view of the casing showing the in section and the pick-up electromagnet,

Figure 6 is an enlarged side view of the casing with the cover removed showing the electromagnet structure.

Figure 7 is a section on the line 7—7 of Figure 5.

Figure 8 is an enlarged view of the pick-up reed, and

Figure 9 is an enlarged view showing the pivotal reed mounting,

Figure 10 is a wiring diagram showing the input connection of the inductive pick-up to the amplifiers and grid control tube for controlling the electro-magnetic brakes of the chucks.

Referring to the drawings, 1 designates a portion of a stand of a conventional printing machine upon which a carriage 2 is reciprocated by a connecting rod 3 mounted upon a crank 4 of a shaft 5 which is turned in any preferred manner—not shown. Mounted on both sides of the stand 1 are lugs 6 in which opposed pairs of stops 7 are provided. Carried by the carriage 2 are two parallel rods 8 the axial alignment of which coincides with the direction of movement of the carriage. Formed in the rods 8 are cam slots 9 to receive the lower extremities of pins 10 which extend downwardly from a printing frame 11 which is supported by the carriage for reciprocation therewith. As the carriage approaches each extremity of its travel the rods 8 strike one pair of stops 7 and consequently their continued movement with the carriage is

arrested. The continued movement of the pins 10 with the printing frame 11 and carriage 2 moves the said pins out of the cam slots 9 and raises the frame 11. As the carriage and frame commence their return stroke and the rods are moved away from the stops 1, balanced springs 12 provided around the extremities of the rods return the latter to their normal positions with respect to the carriage 2 and pins 10 shown in Figure 1. The pins then drop back into the cam slots 9 and the printing frame 11 is again lowered to its normal printing position. Fixed on the stand 1 is a suitable switch 34 having an upwardly projecting operating arm 35 laterally from which a roller 36 extends which rests upon the top of the frame 11. Consequently as the latter is raised and lowered the switch is actuated by movement of the arm 35 in a manner hereinafter described.

Mounted upon the stand 1 and extending transversely of the path of movement of the carriage 2 and beneath the latter is a shaft 15 mounted for intermittent rotation. Fixed upon the shaft 15 are two opposed carrier plates 16 and 17. Radially mounted upon the carrier 16 are a plurality of chucks 18 which are inwardly urged by springs 19; and mounted upon the carrier 17, respectively opposite one of the chucks 18, are corresponding other chucks 20. Each opposed pair of chucks 18 and 20 are intended to support an article A to be printed, moreover the chucks and the article between them are normally free to turn so that the said article may be rotated to the position it is to assume for commencement of the printing operation. Extending axially from each chuck 20 is a spindle 21, Figure 3, which extends through an electro-magnet 22 carried by the carrier plate 17, and held against independent rotation upon the spindle 21 is a brake plate 23 which is drawn against the electro-magnet when the latter is energized, thereby arresting rotation of the chuck and the article A one extremity of which is supported thereby. Since the construction of the chucks 20, the electro-magnets 22 and the various coacting parts have already been described in my co-pending application Serial No. 219,014, now Patent No. 2,211,175, it is not believed necessary to further describe this portion of the structure.

Provided around the outer periphery of the carrier 17, and preferably supported in annular insulated grooves formed therein, are two parallel sets of segmental contacts 24 and 25. Each segment of each set extends through substantially 90° and around like portions of the carrier periphery, by which I mean that the ends of the segments of the two sets are disposed in transverse alignment. Suitably mounted upon a bracket 26, supported by the stand 1, are brushes 29 and 29 which wipe the segments 24 and 25 respectively in turn as the carrier 17 rotates, and mounted upon a similar bracket 27 are brushes 30 and 31 which also wipe the segments 24 and 25 respectively. Between adjacent pairs of segments 24 and 25, insulation 32 is provided by which each adjacent pair of segments is sufficiently spaced that no brush can be in contact with more than one segment at a time. Each of the segments 24 is connected with one extremity of the winding of one of the electro magnets 22, and each opposed segment 25 is connected to the opposite extremity of the winding of that magnet, by connections 33 and 37 respectively, Figure 3.

Supported for rotation by the stand 1 is a stub shaft 38 having a friction disc 39 thereon which

contacts the periphery of each chuck 20 in turn when the latter reaches a predetermined position and rotates it when the said chuck is free to turn. The shaft 38 is provided with suitable means for rotating it as for instance a sprocket wheel 40 over which a chain 41 passes which is driven from any suitable source—not shown.

On a support 101, which is mounted in a manner not shown, a tubular arm 102 is pivotally mounted by a pin 103. A spring 104 connected at one extremity to the support 101 and at its opposite extremity to the arm 102 tends to move the latter about the axis of the pin 103 and thereby move a casing 107 on one extremity of the said arm towards the shaft 15. In threaded engagement with the support 101 is a screw 105 the outer extremity of which is adapted to contact the arm 102 and limit the pivotal movement of the latter. Obviously by adjusting the screw 105 the amount of pivotal movement permitted the arm 102 may be varied.

Suitably supported in the casing 107 is a permanent magnet (Figures 6 and 7) 108, the extremities of which are each in contact respectively with a separate and substantially U-shaped magnetic member 109 and 110 the open ends of which are adjacent and in alignment with one another. A pick-up coil 111 extends into the central portions of both the said members and extends between them. Multi-sided blocks 112 suitably secured to the inner face of the casing 107 have threaded openings therein and project in the central cavities of the members 109 and 110. Clips 113 having screws 114 therethrough in engagement with the threaded block openings bear against the outer faces of the members 109 and 110 and retain the latter in their desired positions. A reed 115 is mounted for limited pivotal movement between the adjacent curved extremities 109a and 110a of the members 109 and 110 respectively and extends through the center of the coil 111. The sides of the reed are preferably covered with rubber as shown at 115a to cushion the reed particularly where it is supported for pivotal movement. Extending transversely of the reed 115 is a tubular internally threaded portion 115b which opens into a hollow portion 115c into which a needle 116 is inserted. A screw 117 in threaded engagement with the tubular portion 115b retains the needle in position. A cover 118 is secured over the casing 107 as by a screw 119 which is screwed into a threaded opening 120 provided in the casing. Extending from opposite ends of the pick-up coil 111 are leads 121 and 122 which extend from the casing through a suitable opening and pass through the tubular arm 102.

I will now describe the electric control means with the aid of the wiring diagram shown in Figure 10.

The leads 121 and 122 of pick-up coil 111 are connected to the primary winding of a transformer 123, the ends of the secondary winding of which are connected to opposite ends of a potentiometer 124 by wires 125 and 126. Extending from a movable arm on the potentiometer 124 is a lead 127 which extends to the grid of an amplifying tube 128, and from the plate of the latter a lead 129 is connected to a condenser 130. From this condenser a lead 131 is provided which is connected to the grid of an amplifying tube 45.

Extending from the lead 129 is a wire 132 terminating in a resistor 133 from which a wire 134 extends to the positive side of a power supply 60b. A lead 135 from the grid of the amplifying tube 128 extends to a resistor 136, and a connec-

tion 137 from the latter is connected to the lead 134. A lead 138 from the cathode and suppressor grid of the tube 128 extends to a resistor 139 and another lead 140 from the said resistor is suitably grounded at 160. A lead 141 from one side of the filament of the amplifying tube 128 is connected to a secondary winding of a transformer 142 and from the latter a wire 143 is also connected to the lead 140. The ends of the primary winding of the transformer 142 are connected to a suitable source of power 60c. One of the windings on the secondary side of the transformer 142 is connected by a lead 144 to the lead 143 and also by a wire 145 and a wire 146 to the plates of a rectifier tube 147. Other leads 148 and 149 are connected to the filament of the rectifier tube 147 and also to another secondary winding of the transformer 142. The lead 149 is connected also to a filter choke 150 which is in turn connected by a wire 151 to the positive side of a source of power 60b. The lead 149 is connected through a condenser 152 by a lead 153 to the lead 143. The lead 151 is connected to the lead 143 through a condenser 155 by a lead 154, and also through a bleeder resistance 157 by a lead 156 to the lead 140.

A lead 71 extends from the plate of the amplifying tube 45 to the grid of a second amplifying tube 46. From the plate of the latter a lead 72 extends through a condenser 57 and resistor 56 to the grid of a gaseous tube 47 which acts as a grid control tube. From the cathode of the gaseous tube a lead 73 extends to a binding post G and from the latter a lead 74 is connected to one side of the switch 34. The opposite side of this switch is connected by a lead 75 to a binding post C, and from this lead a wire 75a also extends to the brush 29 which wipes the segmental contacts 25 as the carrier 17 rotates. The brush 28 which is in the circuit with the brush 29 is connected to the latter through each of the electro-magnets 22 in turn as the shaft 15 turns. From the brush 28 a lead 76 extends which is connected to a binding post D, and from the latter through leads 77 and 99, and through the resistor 52 to the negative side of a source of power 60. Another lead 78 also extends from the post D to a neon tube 61.

The brush 30 which wipes the segmental contacts 24 is connected by a lead 79 to a binding post F and from the latter by a lead 80 to a resistor 50. From the latter connection is made through leads 80a and 99 to the negative side of the source of power 60. The brush 30 is connected through one of the magnets 22 to the brush 31; from the latter a lead 81 extends to a binding post E. This binding post is connected by a lead 82 to the plate of the gaseous tube 47. The binding post G is connected by a lead 83 to the positive side of the source of power 60 and also to an adjustable resistor 55, and from the latter a lead 84 extends through a resistor 51 to the lead 131. From the lead 84 a connection is made to a potentiometer 63 to a connection 84a and through another connection 84b to the cathode of a voltage regulator tube 59. The plate of this tube is connected at 85a to lead 85 extending from a condenser 158 which is also connected by a lead 159 to a ground 160. The lead 85 is also connected to a lead 86 connecting the adjustable resistor 55 with the potentiometer 63.

From the lead 84, which is suitably grounded to the casing of the instrument as shown at 87, a lead 88 extends to the negative side of the power source 60. The cathode of the tube 45 is

connected to an adjustable resistor 64 through a lead 89. A lead 90 extends from the lead 71 through a resistor 54 to a lead 91 which connects the lead 72 through a resistor 48 to the positive side of the power source 60. The lead 91 is connected at 91a to the potentiometer 63. The neon tube 61 is connected to the binding post C by a lead 93. The cathode of the amplifying tube 46 is connected by a lead 94 to the potentiometer 63. The lead 72 between the condenser 57 and the resistor 56 is connected to the resistor 49 by a lead 95; this latter resistor being grounded at 97 to the instrument casing. The lead 82 is connected by a wire 96 to the lead 73, and in the wire 96 intermediately of its length the condenser 58 and resistor 53 are interposed. A binding post H is grounded to the instrument casing at 98.

The operation is as follows: When the needle 116 contacts a projection such as the seam AA 20 on a bottle A it causes a slight movement of the reel 115 in the coil 111. The usual mold seam on a bottle, such as a milk bottle, as commercially furnished, is of very slight elevation, of the order of one one-hundredth of an inch. This sets up a current in the latter which energizes the primary side of the transformer 123. The current in the latter is then stepped up and impresses across the potentiometer 124 and is carried to the grid of the amplifying tube 128 causing the said grid to become more positive so that more current flows to the plate of the said tube. This charges the condenser 130 so that this positive charge is carried by the lead 131 to the amplifying tube 45 and the grid of the latter becomes more positive. This increases the current in the plate of the tube 45 and through the leads 71 and 90 so that the grid of the tube 46 becomes less positive, and results in a reduction of current flow through the lead 72 thereby making the side of the condenser 57 connected to the lead 72 more positive. The reaction of the condenser 57 to this change in potential makes the grid of the gaseous tube 47 more positive and "fires" this tube causing it to function as a relay and energize one of the electro-magnets 22 by allowing current to flow from the power source 60 through the leads 99, 80a, 80, and 79, the resistor 50 and binding post F to the brush 30; and from the brush 31 through the leads 81 and 82, post E, and the plate and cathode of the gaseous tube 47, leads 73 and 83, binding post G, and back to the source of power 60. When this occurs one of the chucks 20 is held immovable on carrier 17 by its magnet 22. The carriers 16 and 17 holding the chucks 18 and 20 are then ready to be rotated by shaft 15 to bring the work A to its printing position. As rotation of the carriers occurs the switch 34 is closed by upward movement of the printing frame 11 which brings the switch contacts 34a and 34b together.

The closing of this switch closes a circuit beginning with the negative side of the source of power 60, through the lead 99, the resistor 52, lead 77, binding post D, lead 76, switch 34, lead 74, binding post G, lead 83, and to the positive side of the power source 60. When rotation of the carrier 17 by shaft 15 occurs the segments 24 and 25 energized through the brushes 30 and 31 also come into contact with the brushes 28 and 29 respectively. Then short circuiting of the brushes 29 and 31 by one of the segments 25 extinguishes the gaseous tube 47, thereby cutting off the supply of power through that tube, but as the brushes 28 and 29 are directly supplied from the power source 60 so long as the holding switch 34

remains closed the magnet 22 between these brushes remains energized until rotation of the carrier 17 has ceased and a downward movement of the printing frame 11 causes the switch 34 to open. Then of course the circuit is broken, and the chuck 20 in conjunction with which that magnet 22 operates is again free to turn.

When the carriers 16 and 17 have been turned so that a bottle A supported between opposed pairs of chucks 18 and 20 is positioned to contact the needle 116, the chuck 20, the bottle A and the chuck 18 supporting the opposite extremity of the latter, are rotated by the disc 39 until a projection upon the said bottle, such as the seam AA thereon, contacts the needle 116. Then a circuit is completed, as hereinbefore described, through the brushes 30 and 31 and the electromagnet 22 connected to the segments 24 and 25 with which the said brushes 30 and 31 respectively are in contact. Rotation of the work is then immediately arrested by the brake plate 23 carried by the spindle 21, which is then drawn into intimate contact with the brake magnet 22. As the carrier 17 is turned to move the work from registering to printing position upward movement of the printing frame 11 closes a circuit through the brushes 28 and 29 and the same brake magnet 22. This short circuits the gaseous tube 47 and breaks the circuit through the brushes 30 and 31, however the same magnet 22 remains energized through the brushes 28 and 29 until the work has arrived at its printing position and the frame is again lowered to its position for reciprocation immediately prior to its next printing stroke. By lowering the frame the switch 34 is opened and the circuit through the brushes 28 and 29 is broken, so that the work about to be printed is again free to rotate in contact with the frame 11 during the printing operation, and the chucks 18 and 20 holding the next bottle A just brought to registering position are also free to be turned by the disc 39.

From the foregoing disclosure it will be evident that the mechanism herein provided, including the sensing means and braking devices operated by the electrical relay and braking circuits, under the control of the sensing needle and its associated devices, serve to carry into effect the general and more particular objects of the invention, by accomplishing exact registry of each bottle or other article to be printed and/or otherwise operated upon, with the operating mechanism, such as the printing frame which is herein illustrated merely by way of example, it being understood that the basic idea of means which underlies the present invention is capable of many embodiments other than the particular physical embodiment selected for illustration and description.

What I claim is:

1. In a registering device for multi-color printing on molded containers having external peripheral mold seams of slight elevation, a chuck for holding said container fixedly thereon, a carrier, pivot mounting means for rotatably mounting said chuck on said carrier, support means for movably supporting said carrier for movement to translate said chuck selectively into an adjusting position or a printing position, said mounting means comprising electromagnetic brake means for locking said chuck in fixed orientation about the pivots on said carrier, a senser, senser mounting means for displaceably mounting said senser for engagement thereof with the periphery of said container as the same is rotated in said

chuck about its pivots and for displacement of said senser when the senser engages a said seam on said container, electromagnetic pick-up means comprising circuit connections, said senser being mounted with a portion thereof in the field of said electromagnetic pick-up means for impressing a voltage impulse on the circuit connections of said electromagnetic pick-up means when said senser is displaced in said field, control circuit means comprising amplifying means and liminal discharge control means actuated by the output of said amplifying means, the circuit connections of said electromagnetic pick-up means being connected to input terminals of said control circuit means, the output connections of said liminal discharge means being connected to said electromagnetic brake means for applying a powerful electric braking impulse to said braking means when said liminal discharge means is actuated, whereby rotation of said chucks and said container on said pivot mounting means into register position with a said seam of low elevation engaging said senser causes locking of said braking means and orientation of said container in printing register.

2. A registering device according to claim 1, said sensor mounting means comprising resilient means positioned between said sensor and said electromagnetic pick-up means for resiliently displaceably mounting said sensor with reference to said electromagnetic pick-up means.

3. A registering device for multi-color printing on molded containers having external peripheral mold seams of slight elevation, comprising a printing machine, a printing frame mounted thereon for movement into a printing position or a rest position, a chuck for holding said container fixedly thereon, a carrier, pivot mounting means for rotatably mounting said chuck on said carrier, support means for movably supporting said carrier for movement to translate said chuck selectively into an adjusting position or a printing position for engagement with said printing frame in its printing position, said mounting means comprising electromagnetic brake means for locking said chuck in fixed orientation about the pivots on said carrier, a senser, senser mounting means for displaceably mounting said senser for engagement thereof with the periphery of said container as the same is rotated in said chuck about its pivots and for displacement of said senser when the senser engages a said seam on said container, electromagnetic pick-up means comprising circuit connections, said senser being mounted with a portion thereof in the field of said electromagnetic pick-up means when said senser is displaced in said field, control circuit means comprising amplifying means and liminal discharge control means actuated by the output of said amplifying means, the circuit connections of said electromagnetic pick-up means being connected to input terminals of said control circuit means, the output connections of said liminal discharge means being connected to said electromagnetic brake means for applying a powerful electric braking impulse to said braking means when said liminal discharge means is actuated, whereby rotation of said chucks and said container on said pivot mounting means into register position with a said seam of low elevation engaging said senser causes instantaneous locking of said braking means and orientation of said container in print register.
